UNITED STATES PATENT OFFICE.

EDGAR E. GREVE, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

HYDRAULIC ROTARY DRILLING-MACHINE.

1,111,535.

Specification of Letters Patent. Patented Sept. 22, 1914.

Application filed April 9, 1913. Serial No. 759,953.

To all whom it may concern:

Be it known that I, EDGAR E. GREVE, a citizen of the United States, residing at Pittsburgh, in the county of Allegheny and State of Pennsylvania, have invented certain new and useful Improvements in Hydraulic Rotary Drilling-Machines; and I do hereby declare the following to be a full, clear, and exact description of the invention, 10 such as will enable others skilled in the art to which it appertains to make and use the same.

My invention relates to the construction of hydraulic rotary drilling machines, and especially to that class wherein the drill stem is rotated by means of a rotary table and intermediate devices which permit of the longitudinal vertical or feed movement of the drill stem.

20 The object of my invention is not only the simplification of the means whereby the drill-stem is actuated from the rotary table, and the normal feed as well as the jumping of the drill stem are permitted, but also the provision of means whereby, when it is desired to support the drill-string, slips and means for moving the same may be readily combined with the rotary table, thus enhancing the usefulness of the rotary drilling 30 machine, as well as its durability, and also saving the time and labor of the operator.

To this end one feature of my invention embraces the combination with a rotary table having a central opening and provided 35 with drive pins, of a bushing having means of engagement with the drive pins of the table and with slips, and slips having means of engagement with the drive pins and with the bushing.

40 There are other, minor, features of invention involving particular combinations and elemental features of construction all of which will hereinafter more fully appear.

In the drawings chosen for the purpose 45 of illustrating my invention, the scope whereof is pointed out in the claims, Figure 1 is a vertical central section of a rotary drilling machine with slips in position for holding a drill stem, and embodying my invention. Fig. 2 is a top plan view of the

rotary table and bushing, with the slips and drill stem in horizontal section, taken in the plane of the line 4—4, Fig. 1.

Like symbols refer to like parts wherever they occur.

55 I will now proceed to describe my invention more fully so that others skilled in the art to which it appertains may apply the same.

In the drawings, 1 indicates suitable skids or sills for the support of the bed-plate 2 which is bolted or otherwise secured to said sills. The bed-plate 2 has an annular race-way 2* for the rolls 3 which support the rotary table and on which said table travels. 60 9 indicates a rotary table provided with a central opening for the reception of bushings and for the passage of the stem of the drill, and surrounding said central opening on the dependent portion of the table is an annular race-way 9* corresponding to race-way 2* for the reception of rolls 3 on which said rotary table 9 rests and travels. 65

70 At the upper part and under surface of rotary table 9 is an annular rack 10 with which the pinion of a driving shaft meshes to cause the rotation of the table 9, and in the periphery of the table intermediate of said rack 10, and race-way 9*, is an annular groove 9* for the reception of a thrust ring 80

11. The thrust ring 11 may be made in sections bolted or otherwise connected when in place in groove 9*, and is provided with pendent straps or foot extensions 11* by which it is bolted to the bed plate 2 to support the rotary table 9 under the thrust of the drive shaft. 85

12 indicates pin holes in the upper surface of rotary table 9 for the reception of drive-pins 13 which drive-pins are secured to the table by cross-pins 13* passed through radially disposed pin holes in the plane of the thrust groove 9*.

The drive pins 13 serve a double purpose, viz., to cause a bushing 14 to revolve with 95 the table, and also as a support on the bed 9 for levers which carry and actuate slips used in pulling out and running in the drill stem. For this latter purpose they are slotted vertically at their upper ends as at 100

13^b for the reception of said levers and are perforated for the reception of pins on which the levers are pivoted.

14 indicates a bushing for the central opening of the rotary table 9 through which bushing passes the drill stem 16, and said bushing is loosely supported in the central opening of table 9 by means of a peripheral flange 14^c, through openings 14^a in which 10 pass the drive pins 13 that cause the bushing 14 to rotate with the table 9.

From time to time in drilling it becomes necessary to pull out, add to and run in the drill stem, and for this purpose in well drilling what are termed elevators are commonly employed, of which two are usually required, the grips of the respective elevators being alternately changed on the stem, as the drill stem is raised or lowered. In lieu of one of 20 said elevators, slips for holding the stem while the grip of the elevator is changed, may be substituted for one of said elevators, and to meet the requirement I have devised for combination with the bushing 14 the 25 slips 20 shown in the drawings. These slips 20 are of general wedge form or tapering having serrated faces 20^a of a form adapted to conform to the stem 16 of the drill with which they are to be employed—in the 30 present instance concave—and provided on their rear or outer surface with ribs or feathers 20^b adapted to engage and slide in the grooves 14^b on the inner face of bushing 14. This feature will prevent any twisting 35 or shifting of the slips. These slips 20 are beveled or rounded off at their lower inner corners as at 20^c and are each suspended from one arm of a lever 21 which lever is pivoted on one of the drive pins 13, the connection 40 between the lever and the slip being in the form of a pin and an elongated slot, as indicated at 21^a, Fig. 1, in order to permit the slips to swing back and away from the stem 16, when the slips are raised by 45 means of said levers 21. This change of position in the slips is indicated in dotted lines Fig. 1 of the drawing.

The construction being substantially such as hereinbefore pointed out the operation of 50 the devices will be as follows: When drilling, rotary motion will be imparted to the rotary table 9 by a driving shaft and a pinion (not shown) which engages the annular rack 10, and the drill stem 16 will be 55 rotated from the table by suitable means interposed between the bushing 14 and drill stem 16.

When it is necessary to pull the drill stem 60 for any purpose, as for instance, the addition or removal of stem sections, the drill stem is raised by means of the usual elevator, and after the mechanism interposed between the bushing 14 and drill stem 16 which is used to cause the rotation of the

drill stem 16 has been removed the slips 20 65 are inserted in the bushing 14 with the ribs 20^b thereof in the grooves 14^b of bushing 14, and the levers 21 which suspend and actuate the slips are inserted in slots 13^b of driving pins 13 and pivoted on said driving pins. 70 The slips 20 may then be allowed to wedge down and will support the drill stem, so that the portion of stem 16 above the slips may be unscrewed and lifted free for the insertion or removal of an intermediate stem 75 section.

If it is necessary or desired to pull the string of drill stem sections when the slips are in the position shown in Fig. 1 of the drawings, the slips will not interfere therewith, as owing to the bevel 20^c on the inner lower corners of the slips and the suspension of the slips on levers 21 the collars or couplings of the drill stem sections will be enabled to force the slips upward and backward as indicated in dotted lines, Fig. 1, which will readily permit the passage of the 80 couplings of the drill stem.

When the drill stem is allowed to descend slightly the slips will automatically grip 90 and hold the drill stem so that the grip of the elevator on the drill stem can be changed from time to time in pulling or running in the drill stem so that but a single elevator 95 will be required for such purposes.

In order to release the drill stem from the grip of the slips at such times as the elevator has control of the drill stem all that is necessary to be done is to manipulate the levers 21 to elevate the slips and lift them 100 back into the position shown in dotted lines, Fig. 1 of the drawings.

It will be noted that in the construction herein described the engagement and disengagement of the drill stem and rotary 105 table are automatically effected by the manipulation of the drill stem, and consequently loss of time and labor in manipulating is avoided.

Having thus described my invention, what 110 I claim and desire to secure by Letters Patent is:

1. In a rotary drilling machine, the combination with a rotary table having an axial opening for the passage of a drill stem, and provided on its upper surface with drive pins, of a bushing having openings for the passage of the drive pins, levers pivoted on the drive pins, and slips suspended from the levers, said slips provided with means for 115 engaging the bushing.

2. In a rotary drilling machine, the combination with a rotary table having an axial opening, of a bushing having an opening in the axis of rotation of the table, and slips suspended in said bushing, said slips having beveled lower surfaces for engaging the 125 collars on a drill stem.

3. In a rotary drilling machine, the combination of a rotary table having an axial opening, a bushing having an axial opening, slips suspended in the axial opening of said bushing and levers from which the slips are suspended, said levers having fulcrums on the rotary table.

4. In a rotary drilling machine, the combination with a rotary table having an axial opening and provided on its upper surface with drive pins, of a bushing having open-

ings for the passage of the drive pins, slips provided with means for engaging the bushing and levers fulcrumed on the drive pins said levers having loose pin and slot connections with the slips. 15

In testimony whereof I affix my signature, in the presence of two subscribing witnesses.

EDGAR E. GREVE.
